FIG. 3.

INVENTOR

ANDREW JOHNSON,

BY *John Kee,*

ATTORNEYS

UNITED STATES PATENT OFFICE.

ANDREW JOHNSON, OF BREWSTER, WASHINGTON.

FRUIT HANDLING AND SORTING APPARATUS.

Application filed January 5, 1924. Serial No. 684,611.

To all whom it may concern:

Be it known that I, ANDREW JOHNSON, a citizen of the United States, and a resident of Brewster, in the county of Okanogan 5 and State of Washington, have invented certain new and useful Improvements in Fruit Handling and Sorting Apparatus, of which the following is a specification.

This invention relates to an apparatus 10 designed to facilitate sorting and packing of fruit such as apples or the like.

The object of the invention is to provide an apparatus of this character which is of extremely simple and durable construction, 15 adjustable to meet various conditions and requirements and adapted to be effectively operated and to be conveniently and readily controlled to carry out its intended purposes.

20 Other objects and advantages of the invention reside in certain novel features of the construction, combination and arrangement of parts which will be hereinafter more fully described and particularly 25 pointed out in the appended claims, reference being had to the accompanying drawings forming part of this specification, and in which:

Figure 1 is a fragmentary perspective 30 view, showing the preferred embodiment of the invention;

Figure 2 is a fragmentary detail view, partly in section and partly in elevation, 35 showing a portion of the vertical shaft and the structure of the frame carried thereby; and

Figure 3 is a diagrammatic view in plan showing the mode of use of the apparatus.

Referring to the drawings wherein for the 40 sake of illustration is shown the preferred embodiment of the invention, the numeral 10 designates a rotatable vertical shaft which is journaled at its upper and lower ends in suitable bearings (not shown). A 45 sorting table, designated generally at 11 is provided and includes a frame, designated generally at 12 and a pocket or compartment forming body, designated generally at 13.

50 The frame 12 includes a pair of hubs 14, these hubs being of similar construction and being fitted on the shaft 10. Each hub includes a body portion 15 and a keeper ring 16 spaced from and connected to the body portion by a plurality of radial arms 17 integral with or suitably secured to the

body portion 15 of the ring 16. The hubs 14 are spaced from each other on the shaft 10 and are adjustably secured to and supported upon the shaft. Preferably the 60 shaft 10 is provided with a series of spaced transverse openings 18 and the body portion 15 of each hub includes a similar transverse opening 19. The hubs 14 may be adjusted along the shaft 10 so that their 65 transverse opening 19 alines with any of the openings 18 of the shaft 10. With the openings of the hub 14 and shaft 10 so alined pins 20 are fitted in the alined openings to hold the hubs in adjusted position on the 70 shaft. The frame 12 also includes a plurality of radially arranged, angularly spaced and horizontally disposed supporting bars 21. The inner end of each bar 21 carries a hook 22. The hooks 22 are engaged with 75 the keeper ring 16 of the upper hub 14 and preferably the arrangement is such that one such hook 22 is engaged with the portion of the ring 16 comprehended between each adjacent pair of arms 17. In this manner 80 each supporting bar 21 is detachably connected to the upper hub 14. A plurality of brace bars 23 are provided, there being one brace bar 23 for each supporting bar 21. 85 Each brace bar 23 is provided with a longitudinal series of openings 24 adjacent its upper end and the supporting bars 21 are provided with a similar series of openings 25 intermediate their ends. The openings of the series 24 in the brace bars 23 are 90 adapted to be selectively alined with the openings 25 of the supporting bars 21 and through the alined openings removable pins or keys 26, such as cotter pins or the like, 95 are fitted and releasably secured. By this arrangement the upper ends of the brace bars 23 are adjustably connected to the supporting bars 21. The lower end of each brace bar 23 is notched or bifurcated as at 100 27 and the walls of the notches 27 fit around portions of the keeper ring 16 comprehended between adjacent arms 17 of the lower hub 14. In this manner the lower ends of the brace bars are detachably connected to the lower hub 14.

105 The compartment or pocket forming body 13 consist of an annular or endless piece of fabric or other flexible material which is laid upon the supporting bars 21 and releasably secured to these bars if desired. The sections or portions of the pocket forming member 13 comprehended between adjacent bars 110

- 21 falls into a trough or cup-like containers, designated at 28, and each such container is well defined and isolated from adjacent containers by supporting bars 21.
- 5 In use, the apparatus is arranged in units on each side of the line of delivery of the boxes of fruit from the orchard. An instance of such arrangement is illustrated in Figure 3 where each unit is designated at A.
- 10 The boxes containing the fruit which is delivered from the orchard are designated at B and the packing benches at P. The apples or other fruit contained in the boxes B are taken therefrom by the sorter and distributed to their respective compartments or pockets provided in the several units of the device. All compartments of each apparatus or unit are readily accessible since the sorting table is turnable. The turnable 20 mounting of the sorting table also renders the pockets or compartments 28 accessible to the packers. The sorters and packers may readily manipulate the sorting tables by grasping the extremities of the bars 21 and turning these tables from the portion 25 of the bars thus grasped.
- It is to be understood that the apples as picked are delivered in their boxes by a conveyor to the sorter, who manually sorts 30 the apples as to sizes and qualities by placing the various grades and sizes in their respective containers or pockets in the sorting table. The sorted apples or other fruit are also delivered to the packers by means 35 of the sorting table which is movable or turnable for this purpose.
- I claim:
1. In combination, a rotatable vertical

shaft, and a sorting table comprising a frame carried by the shaft and including spaced horizontal bars, and an endless flexible pocket forming body supported upon the bars.

2. In combination, a rotatable vertical shaft, and a sorting table comprising a frame carried by the shaft and including spaced horizontal bars, and an endless flexible pocket forming body supported upon the bars, the outer ends of the bars of the frame projecting beyond the outer peripheral portion of the pocket forming the body and providing a means whereby the sorting table and shaft may be rotated.

3. In combination, a rotatable vertical shaft, and a sorting table comprising a frame including upper and lower hubs adjustably fixed to the shaft, spaced horizontal bars detachably connected to the upper hub and brace bars adjustably connected to the horizontal bars and detachably connected to the lower hub, and an endless flexible pocket forming body supported upon the horizontal bars.

4. In combination, a rotatable vertical shaft, and a sorting table comprising a frame including upper and lower hubs adjustably fixed to the shaft, said hubs having keeper rings, spaced horizontal bars having hooks engageable with the keeper ring of the upper hub, and brace bars adjustably connected to the horizontal bars and having their lower ends notched and engaged with the keeper ring of the lower hub, and an endless flexible pocket forming body supported upon the horizontal bars.

ANDREW JOHNSON.
